BRINE MIXING APPARATUS

Filed Jan. 15, 1929

FIG. 1

FIG. 3

FIG. 4

INVENTOR

A. Fazio

BY C. B. Birkenbeul
ATTORNEY

UNITED STATES PATENT OFFICE

ANTONIO FAZIO, OF PORTLAND, OREGON

BRINE-MIXING APPARATUS

Application filed January 15, 1929. Serial No. 332,722.

This invention relates generally to the pickling industry with special reference to means for preparing brine solutions used in this industry.

5 The main object of this invention is to enable the packer to prepare his brine solutions with the expenditure of the least amount of time and labor possible, and at the same time completely mixing and dissolving all of the 10 salt.

The second object is to eliminate the necessity of providing and using elevators for carrying the bags of salt into an elevated mixing tank, or the necessity of carrying these bags 15 up ladders or stairways.

These, and other objects, will become more apparent from the specification following as illustrated in the accompanying drawing, in which:

20 Figure 1 is a perspective view of the apparatus. Figure 2 is a vertical section through the mixing tank taken along the line 2-2 in Figure 1. Figure 3 is a plan of the storage tank. Figure 4 is a section through 25 the three-way valve.

Similar numbers of reference refer to similar parts throughout the several views.

Referring in detail to the drawing, there is 30 illustrated the usual elevated storage tank 10 from which brine can flow by gravity through an outlet pipe 11 and be distributed through the hose 12 to the various barrels 13, under the control of the valve 14.

The object in having the tank 10 elevated 35 is to provide a sufficient head to the brine to make it possible to quickly refill the barrels 13 as the brine is absorbed and evaporated.

In addition to the above described apparatus there is added the mixing tank 15 provided with a closure 16 which may be clamped 40 in place by means of the hinge clamps 17 making the tank 16 pressure tight when desired. Within the tank 15 is a cylindrical screen 18 whose top 19 is closed and whose lower end 45 is provided with an outlet pipe 20 which opens into an ejector 21 whose discharge pipe 22 is provided with a check valve 23, said pipe discharging into the tank 10, preferably in the manner shown in Figure 3, namely with its 50 tip 24 along the outer side of the tank 10 for

the purpose of imparting a whirling motion to the water and more completely mixing the solution, or rather providing a uniform degree of saturation throughout the entire volume of brine. The inlet pipe 25 of the ejector 55 21 is connected to one port of a three-way valve 26, from which valve a pipe 27 connects with the mixing tank 15 and a third pipe 28 connects with a water meter 29 whose pipe 30 connects with the pressure water system. 60

The operation of the device is as follows: If it is desired to produce a given number of gallons of brine of a certain strength, the required amount of salt is measured out and deposited within the mixing tank 15 around the 65 sides of the screen 18. The closure 16 is then put in place and water is admitted to the tank 15 by means of the valve 26, the meter 29, of course, being read to enable the operator to control the amount of water passing through 70 the apparatus. Before the desired amount of water has passed through the meter, the three-way valve 26 is turned in a manner to cut off the flow through the pipe 27 and to allow same to flow through the pipe 25, causing the 75 ejector 21 to draw whatever water remains within the tank 15 and to discharge same into the tank 10. In order to make it possible to withdraw this water from the tank 15 it is necessary to provide an air valve 31 which can 80 be opened to allow the air to escape when water first enters the tank 15 and closed as soon as the tank 15 is filled with water, and again re-opened when the water is being withdrawn by the ejector. 85

There are, of course, numerous ways in which this task can be accomplished, there being illustrated only one form of the apparatus representing the preferred form of 90 the invention.

I claim:

1. A brine mixing apparatus consisting of a mixing tank, a closure for said mixing tank, a screened outlet for said mixing tank, an ejector adapted to draw liquids through said outlet, a three-way valve for admitting water to said tank or to said ejector whereby water may be forced through said tank or around said tank in a manner to withdraw any water 95 which has collected therein. 100

2. In a brine mixing apparatus the combination of a mixing tank having a screened well formed therein, a removable closure for said tank, an ejector arranged to draw liquids from said screened well, a three-way valve having one side discharging into said tank, a second side discharging into said ejector and a third side connected to a water supply means for measuring the water passing through said three-way valve, and means for storing the liquid discharged from said ejector.

3. In a brine mixing apparatus the combination of a mixing tank with a storage tank elevated above said mixing tank, a pipe for supplying water to said mixing tank, a pipe connecting the bottom of said mixing tank with said storage tank, and valve means for controlling the flow of water through said mixing tank into said storage tank, consisting of a three-way valve having one discharge side opening into said mixing tank, together with an ejector having one intake side communicating with the three-way valve and the other intake side communicating with said mixing tank and having the discharge side communicating with said storage tank.

4. In a brine mixing apparatus the combination of a mixing tank having a removable closure, an elevated storage tank from which brine can be drawn by gravity, a pipe opening into said storage tank through which water may be delivered under pressure, a meter for measuring the flow of water into said mixing tank, a three-way cock for controlling the flow of water from said meter to said mixing tank, an outlet from said mixing tank discharging into said storage tank having a check valve therein, an ejector in said outlet pipe, a by-pass connecting said ejector with said three-way cock whereby the water flowing through said meter can be utilized to empty the mixing tank and discharge its contents into the storage tank, and an air vent in said closure for permitting the filling and emptying of said mixing tank when said closure is in position.

ANTONIO FAZIO.
